UNITED STATES PATENT OFFICE.

JOHN REED, OF CORBRIDGE-UPON-TYNE, ENGLAND.

EXHAUST SILENCER FOR INTERNAL-COMBUSTION ENGINES.

Application filed May 6, 1921. Serial No. 467,484.

To all whom it may concern:

Be it known that I, JOHN REED, a subject of the King of Great Britain, residing at Corbridge House, Corbridge-upon-Tyne, 5 Northumberland, England, have invented certain new and useful Improvements in Exhaust Silencers for Internal-Combustion Engines, of which the following is a specification.

- 10 The object of the present invention is to provide an improved silencing device of simple construction, whereby noises caused by gases or air leaving a chamber will be entirely obviated, or so much minimized as 15 to be negligible. The silencer according to this invention and as hereafter described, is particularly applicable for use with internal combustion engines, and may be employed for silencing the exhaust gases thereof, so 20 that the same shall be practically inaudible while producing the least possible back pressure.

According to this invention an elongated outer casing of substantially equal diameter 25 throughout its length is constructed having an open-ended tube entering at one end and extending to near the opposite closed end of the outer casing, the said open-ended tube having series of holes formed in its wall 30 within the casing, the holes towards the inner end of the tube being larger in area than the holes towards the entering end of the tube; or alternatively the tube within the casing may be formed with a slot or slots 35 which increase in area as they approach the inner end of the said tube. The outer casing is formed with an opening or provided with a tube communicating with the outer casing adjacent to the entrance end of the 40 aforesaid open-ended tube having the slots or holes.

In a specification of a prior United States Patent Application Serial No. 376592 filed 26th April 1920, there has been described a 45 silencer device for the exhaust gases of internal combustion engines which consisted of a conical outer casing having an open-ended tube entering said casing at its larger end and extending axially therein and terminating adjacent to the smaller end of the conical casing, and such a tube was described as having a series of apertures within the casing increasing in area as they increased in distance from the larger end of 50 the said casing, and a pipe or pipes were to

be fitted to convey exhaust gases from the engine to within the casing at its larger end and the pipes were to be fitted tangentially to cause the gases to spin around the exterior of the internal tube within the said casing. 60

The present invention therefore is primarily differentiated from that described in specification Serial No. 376592 in that in the construction according to the present invention the case is not conical, the open-ended 65 tube having the graduated apertures does not necessarily extend coaxially with the outer casing, and furthermore the gases are not conveyed to the outer casing in such manner as to produce a spinning motion. 70

In the apparatus above generally outlined according to the present invention, when exhaust gases from an engine are being dealt with, the same are introduced into that end of the outer casing distant from the open 75 end of the tube having the graduated holes or tapered apertures in its wall and find their exit by the latter tube.

The invention will now be further described with reference to the example of 80 construction shown on the accompanying drawings.

Fig. 1 is a longitudinal sectional elevation of a silencing device according to this invention suitable for the passage and silencing of the exhaust gases of an internal combustion engine, and Fig. 2 is a vertical cross section on the line X—Y of Fig. 1.

The silencer consists of an elongated closed casing 1, and the two ends 2, 3 in this 90 example will be referred to respectively as the forward and rearward ends.

Entering the rearward end 3 of the casing by a suitable joint is what will be termed in this example an outlet tube 4 which extends 95 inside the casing 1 to adjacent the forward end 2 where the end of the outlet tube 4 is open, the said outlet tube being also open at its rearward end externally of the rear end of the casing 1. 100

The wall of the outlet tube 4 within the casing 1 may be formed with a series of holes graduated or varying in diameter, that is to say the holes towards the rearward end 3 of the casing in the wall of the 105 outlet tube being smaller in area than the holes as they approach the front end of the casing. Alternatively and as shown at Figs. 1 and 2, instead of the holes a slot or slots 5 is or are formed through the wall of the 110

outlet tube 4, the slots increasing in area as they approach the open end of the outlet tube.

In the construction shown the inlet tube 6 enters the forward end 2 of the casing 1, and its inner open end terminates adjacent to the rearward end 3 of the interior of the casing, so that the gases delivered into the casing are so delivered adjacent to the rearward end. Obviously such an inlet tube 6 for the exhaust gases might enter the casing directly at or near the rearward end 3 when no further tubing would be required in the interior of the casing, or equally obviously the tube 6 might enter the casing at any point and then pass through the interior of the casing, but it is one of the essentials of this invention that the gases should pass to the casing 1 adjacent to the rear end 3 and leave through the graduated slots or open end of the tube 4 at the opposite end of the casing, and in dealing with the exhaust gases from the engine cylinders, the said gases must enter the casing 1 near the end 3 and leave the casing through the graduated apertures or slots 5 of the tube 4 and through the open end thereof near the opposite end of the casing 1.

The forward and rearward ends of the casing may be sloped or curved, and the said ends are preferably of thicker metal than the remainder of the casing; if made of sheet metal the ends are preferably slightly coned or domed to prevent any possibility of their producing a drumming action or acting as diaphragms, and if so formed they will have the further advantage of deflecting the exhaust gases entering the silencer away from the inlet tube 6 and thus reducing back pressure, particularly when the inlet tube 6 extends through the length of the interior of the casing as illustrated in this example.

The action of the silencer is as follows. When an impulse, due to the liberation of the exhaust gas from the engine enters the silencer, a wave of pressure is set up and travels up the silencer from the rear to the front end. Some of this immediately escapes into the outlet tube 4 through the small end of the graduated slot or series of holes 5. The remainder travels up the silencer from the rear to the front being gradually relieved as it travels up the silencer by the graduated slot or series of holes 5, until, when it reaches the front end 2, the whole of the remainder is allowed to escape down the open end of the outlet tube 4.

As part of the impulse escapes immediately through the small end of the slot or series of holes 5 into the outlet tube 4 whilst the remainder has to travel varying distances up to a maximum of twice the length of the slot or series of holes 5, that is once up outside the outlet tube 4 to the open end and back inside it, the effect is to spread out

the sound of the impulse over an appreciable period of time and thus reduce its intensity at any one time. In the case of engines with a large number of cylinders running at a high speed this period of time 70 may actually be greater than the period between the exhausting of one cylinder and the next, and thus almost complete silence may be obtained.

The advantages are that as the silencer 75 does not depend on baffling to obtain silence, the passages may be large and thus reduce back pressure to a minimum. Further the effect of sootting up is not to cause back pressure but merely to close up the small 80 end of the slot or series of holes 5, thus in effect shortening it and thus only reducing the degree of silence instead of causing back pressure. Further as the passages can be large they are not as liable to soot up as in the usual construction of silencers. The outlet tube 4 can be made easily removable for cleaning. The silencer may be supported in any convenient manner such as by straps round the barrel or by brackets. 90

The tubes 4, 6 may be supported and held in position by any suitable means, such as by brackets 7, 8.

What I claim as my invention and desire to secure by Letters Patent is:— 95

1. In a device for silencing rapidly flowing gases, an elongated outer casing closed at one end and of substantially uniform diameter throughout its length, in combination with a tube open at both ends traversing nearly the whole length of said casing, said tube being provided with communicating means for permitting the passage of a portion of said gases between its interior space and the surrounding space within the 100 casing, said means being of maximum area at the open end of said tube adjacent the closed end of said casing, and of gradually diminishing area towards the other end thereof.

2. In a device for silencing rapidly flowing gases, an elongated outer casing closed at one end and of substantially uniform diameter throughout its length, in combination with a tube open at both ends traversing nearly the whole length of said casing, said tube having a tapering longitudinal slot the maximum width of which is at the open end of said tube adjacent the closed end of said casing. 110

3. In a device for silencing rapidly flowing gases, an elongated outer casing closed at one end and of substantially uniform diameter throughout its length, in combination with a tube open at both ends traversing nearly the whole length of said casing, said tube having a plurality of slots giving communication between its interior space and the surrounding space within the casing, the maximum combined area of said 125 130

slots being about the open end of said tube adjacent the closed end of said casing and said combined area gradually diminishing towards the other end of said tube.

5 4. In a device for silencing rapidly flowing gases, an elongated outer casing closed at one end and of substantially uniform diameter throughout its length, in combination with a tube open at both ends traversing nearly the whole length of said casing, said tube having a trumpet-mouthed longitudinal slot, the flared end of which is at the open end of said tube adjacent the closed end of said casing.

10 5. In a device for silencing rapidly flowing gases escaping from an internal combustion engine, an elongated outer casing closed at one end and of substantially uniform diameter throughout its length, an

20 open-ended tube entering at one end and extending to near the opposite closed end of said casing, said tube being formed with a slot which increases in diameter as it approaches the inner end of said tube, and means for admitting said escaping gases to the interior of said casing adjacent that end of said casing at which said tube enters.

25 6. In a device for silencing rapidly flowing gases escaping from an internal combustion engine, an elongated outer casing closed at one end and of substantially uniform diameter throughout its length, an open-ended tube entering at one end and extending to near the opposite closed end of

30 said casing at one side of the major axis of said casing, said tube being formed with a slot which increases in diameter as it approaches the inner end of said tube, in combination with a second tube entering said

35 casing through said closed end and extending parallel with the said first named tube to deliver said escaping gases to the interior of said casing adjacent that end of said casing at which said first named tube enters.

40 45 7. In a device for silencing rapidly flowing gases escaping from an internal combustion engine, an elongated outer casing of substantially uniform diameter throughout its length and having an inclined closed end, an open-ended tube entering said casing at the end opposite said inclined closed end and extending nearly to said inclined closed

end, said tube being formed with a slot which increases in diameter as it approaches the inner end of said tube, and means for 55 admitting said escaping gases to the interior of said casing adjacent that end of said casing at which said tube enters.

8. In a device for silencing rapidly flowing gases escaping from an internal combustion engine, an elongated outer casing of substantially uniform diameter throughout its length and having two inclined closed ends, two open-ended tubes entering said casing adjacent said closed ends and each of 60 said tubes extending in parallel relation to the other tube nearly to the opposite inclined end of said casing, one of said tubes being formed with a slot which slot increases in diameter as it approaches the inner end of said tube.

9. In a device for silencing rapidly flowing gases escaping from an internal combustion engine, an elongated outer casing of substantially uniform diameter throughout 75 its length and having a domed closed end, an open-ended tube entering said casing at the end opposite said domed closed end and extending nearly to said domed closed end, said tube being formed with a slot which increases in diameter as it approaches the inner end of said tube, and means for admitting said escaping gases to the interior of 80 said casing adjacent that end of said casing at which said tube enters.

10. In a device for silencing rapidly flowing gases escaping from an internal combustion engine, an elongated outer casing of substantially uniform diameter throughout 90 its length and having two domed closed ends, two open-ended tubes entering said casing adjacent said closed ends and each of said tubes extending in parallel relation to the other tube nearly to the opposite domed end of said casing, one of said tubes being 95 formed with a slot which slot increases in diameter as it approaches the inner end of said tube.

In witness whereof I have hereunto set my hand in the presence of two witnesses.

JOHN REED.
